SHIELDED ELECTRODE TUBE

Ralph M. Heintz, Palo Alto, Calif., assignor to
Heintz & Kaufman, Ltd., San Francisco, Calif.,
a corporation of Nevada

Application September 6, 1933, Serial No. 688,328

8 Claims. (Cl. 250—36)

My invention relates to a thermionic tube and more particularly to a tube in which the anode and cathode are separated by an electrostatic shield which also acts as a control electrode.

5 Among the objects of my invention are: To provide a thermionic tube capable of oscillation at ultra high frequencies; to provide a thermionic tube in which a control electrode acts as an electrostatic shield between anode and cathode; to 10 provide an electrostatic shield separating anode and cathode as well as their associated circuits; to provide a thermionic tube and circuit therefor in which the control electrode is grounded; and to provide a simple and efficient generator and amplifier of ultra high frequencies.

Other objects of my invention will be apparent or will be specifically pointed out in the description forming a part of this specification, but I do not limit myself to the embodiment of my invention herein described, as various forms may be adopted within the scope of the claims.

Referring to the drawings which illustrate several embodiments of my invention, all somewhat diagrammatically represented for the sake of clearness:

Figure 1 is a longitudinal sectional view of a thermionic tube embodying my invention.

Figure 2 is a cross sectional view taken as indicated by the line 2—2 in Figure 1.

30 Figure 3 is a longitudinal sectional view of another embodiment of my invention.

Figure 4 is a longitudinal sectional view of still another embodiment.

Figure 5 is a longitudinal view of still another example.

Figure 6 is a longitudinal view of an example having concentric electrodes.

Figure 7 is a circuit diagram reduced to lowest terms of the tube of my invention connected up as an oscillation generator.

In the generation and amplification of ultra high frequency radio waves interelectrode capacities, especially those capacities which occur between electrodes of fluctuating potentials, become

45 so important as to require, in many cases, special neutralizing expedients. Such expedients are invariably losses and reduce efficiency of conversion.

In addition, at wavelengths around three meters and below, the usual type of three-electrode tube is practically useless for the generation of any appreciable amount of oscillating current.

Attempts have heretofore been made to separate the fluctuating potentials by using opposed grid and anode, and inserting the filament between them. The filamentary cathode being grounded,

acts as a partial shield between the other electrodes. Such a construction, while an improvement over ordinary types of tubes, is subject to the disadvantage of having a low amplification factor, and as the control is electrostatic the 5 shielding effect of the cathode can only be increased at the expense of loss of control.

I have, however, been able to completely shield the fluctuating electrodes in a thermionic tube. In broad terms my invention comprises utilizing 10 the grid as an electrostatic shield between anode and cathode. I prefer to connect the anode and cathode to tuned circuits, and extend the material of the grid to act as a complete shield between the anode and cathode and their associated circuits. It is convenient to extend the grid to a point where it will cooperate with an external shield separating the circuits to form 15 effective electrostatic shield. I may desire to have the grid material actually pass through the envelope to contact the external shield, or I may bring the grid material to the inner surface of the envelope wall and so form the envelope that the external shield comes sufficiently close to the grid material as to form a completely effective 20 shield when the grid is connected to the external 25 shield.

The broad aspects of my invention may be further understood by reference to the drawings.

Referring directly to the embodiment of my 30 invention shown in Figures 1 and 2, a grid electrode 1 is preferably formed out of chrome iron of a composition to which glass may be sealed. The grid is preferably of circular shape and is provided with a central aperture 2 crossed by 35 grid wires 4.

Sealed to the grid electrode on one side is an anode envelope portion 5 and on the other side a cathode envelope portion 6, the seals 7 preferably registering on opposite sides of the grid 40 electrode, to leave an exterior grid flange 9 projecting outside of the combined envelopes.

As the envelope portions are connected by the central aperture 2, the combined envelopes may be considered as a single tube envelope, the grid 45 electrode passing through its walls.

An anode 10 is mounted in the anode envelope portion on an anode lead 11 sealed through the envelope wall, and in the cathode envelope portion, on the other side of the grid electrode, is 50 positioned a cathode 12 supported by cathode leads 14. The anode and cathode are thus completely separated within the tube by the grid electrode.

The grid electrode may then be continued 55

away from the tube by the use of an exterior shield 15 which is provided with an envelope aperture 16. The tube is inserted in this aperture, which is preferably larger than the envelope but smaller than the grid flange 9, the tube being supported by fastening the grid flange to the shield by screws 17, the positioning being preferably concentric so that no openings are present in the combined shield.

10 The combined shield, formed by contact of the grid with the exterior shield, is preferably used to separate a pair of tuned circuits, as shown in Figure 7. Here the grid electrode 1 is shown grounded and may be extended to completely surround one or both of the tuned circuits. An anode tuned circuit comprising the anode inductance 19 and anode variable capacity 20 is connected in series with an anode source 21 to the anode, the other end of the anode source 20 going to a common anode-cathode point 22, grounded for radio frequency through condenser 23. The anode source is also preferably shunted by a by-pass capacity 24.

As the cathode 12 requires two leads for conducting current thereto, it is desirable to include both leads in a cathode-tuned circuit. This may be done in several ways, all well known in the art, but I prefer to make one lead a hollow conductor 25 wound into an inductance, the other lead 26 being run through the tube. The hollow conductor 25 and inner lead 26 are then connected to a cathode source 27, the ends of the hollow conductor being shunted by a cathode variable capacity 29 to complete the cathode-tuned circuit. The hollow conductor side of the cathode source is then connected to the common anode cathode point 22.

The circuit thus formed will cause the tube to oscillate, having parallel tuned-anode tuned-cathode circuits, behaving in much the same manner as the well known tuned-grid tuned-plate circuit, in which the coupling between the two circuits is the anode-grid capacity. In this case the coupling is the anode-cathode capacity.

45 The tube and circuit described, however, differ from the ordinary tuned-grid tuned-plate combination in that in this example the two fluctuating electrodes are separated by the grounded grid. The electron stream, however, is under 50 complete control as the grid is in its usual position for proper control. Furthermore, as control is increased, as by making the grid wires finer and closer together, the shielding becomes better and reaches the point where it is virtually complete.

The tube as above described in combination with the related circuits will oscillate freely and supply substantial amounts of power of high frequencies at which the usual tube and associated 60 circuits fail.

The remaining figures, 3, 4, 5, and 6 show various embodiments of the invention.

In Figure 3, the envelope is provided with an expanded portion 30 in which the grid electrode 65 is positioned. The exterior shield 15 has attached thereto a pair of cooperating flange rings 31, the inner portions of which are shaped to enclose the expanded portion and thus overlap the periphery of the grid electrode. The internal and exterior 70 portions are then connected through a grid seal 32.

In Figure 4 the anode end of the envelope is somewhat expanded and of larger diameter than the cathode end. A shoulder 33 thus may be used 75 to position the tube in the envelope aperture,

which in this case closely fits the cathode end. The grid electrode is extended above the shoulder in the enlarged anode end and thus overlaps the external shield. The usual connection is made through the grid seal 32.

In Figure 5, the grid electrode fits the envelope and is formed with a peripheral flange 34 which extends parallel to the envelope. The exterior shield 15 is provided with a flange ring 35 on which an exterior flange is turned. The tube is 10 positioned so that the two flanges are opposite and the grid connected to the shield through the grid seal 32.

The embodiment shown in Figure 6 is practically identical with that shown in Figure 1, except that in this example the grid control portion and the anode are concentric cylinders, the grid control wires 4 being supported by a tube 36 extending from the body of the grid electrode which is sealed through the envelope walls as shown in Figure 1. The cathode leads pass along this tube, and the grid wires are provided with a top cap 37 to complete the shielding.

While the shielding provided by the embodiment shown in Figures 1 and 6 might seem to be better than the shielding provided in the remaining embodiments, the leakage space is only that provided by the thickness of the envelope wall which is usually quite thin. The examples shown wherein the grid electrode is not sealed through the wall are cheaper to manufacture, and tubes using this construction will oscillate at frequencies well below those obtained by ordinary tubes. However, the complete shield formed by extending the shield through the envelope walls is to be preferred where a slight increase in cost is no deterrent in obtaining the most efficient production of oscillating power.

It should also be noted that when the grid electrode is sealed through the walls, the tube 40 may be mounted on the panel or shield by the direct fastening of the exterior portion to the panel, thus obviating a base of any kind, as connections from the associated circuits can be made to the leads of the remaining electrodes on the proper side of the shield.

I claim:

1. In combination with an electrostatic shield for separating a pair of tuned circuits, a thermionic tube comprising an envelope containing an anode, a cathode, and a control electrode positioned between said anode and cathode, said control electrode forming a continuing portion of said shield.

2. In combination with an electrostatic shield for separating a pair of tuned circuits, a thermionic tube comprising an envelope containing an anode, a cathode, and a control electrode positioned between said anode and cathode, said control electrode passing through the wall of said envelope to form a continuing portion of said shield.

3. In combination with an electrostatic shield for separating a pair of tuned circuits, a thermionic tube comprising an envelope containing an anode, a cathode, and a control electrode positioned between said anode and cathode, said control electrode having a central perforate portion and a peripheral imperforate portion, said imperforate portion being extended through the walls of said envelope to form a continuation of said shield.

4. In combination with an electrostatic shield for separating a pair of tuned circuits, a thermionic tube comprising an envelope containing an

anode, a cathode, and a control electrode positioned between said anode and cathode, said control electrode forming a continuing portion of said shield, one of said tuned circuits being connected to said anode and the other to said cathode.

5. In combination with an electrostatic shield for separating a pair of tuned circuits, a thermionic tube comprising an envelope containing an anode, a cathode, and a control electrode positioned between said anode and cathode, said control electrode passing through the wall of said envelope to form a continuing portion of said shield, one of said tuned circuits being connected 10 to said anode and the other to said cathode.

6. In combination with an electrostatic shield for separating a pair of tuned circuits, a thermionic tube comprising an envelope containing an anode, a cathode, and a control electrode positioned between said anode and cathode, said control electrode having a central perforate portion and a peripheral imperforate portion, said imperforate portion being extended through the 15

walls of said envelope to form a continuation of said shield, one of said tuned circuits being connected to said anode and the other to said cathode.

7. In combination with a grounded electrostatic shield for separating a pair of tuned circuits, a thermionic tube comprising an envelope containing an anode, a cathode, and a control electrode positioned between said anode and cathode, said control electrode forming a continuing 10 portion of said shield, one of said tuned circuits being connected to said anode and the other to said cathode.

8. In combination, a pair of tuned circuits, an electrostatic shield positioned to prevent coupling between said circuits, said shield having an aperture therein, and a thermionic tube having an envelope containing an anode, a cathode and a grid therebetween, said grid being peripherally extended through said envelope to close said aperture, one of said circuits being connected to said anode, the other to said cathode. 15 20
